Primary Examiner — Marianne Pandozzi

(74) Attorney, Agent, or Firm — Barnes & Thornburg
LLP(57) **CLAIM**

What is claimed is the ornamental design for a beverage maker, as shown and described.

DESCRIPTION

FIG. 1 is a perspective view of a beverage maker showing my new design;

FIG. 2 is a front elevational view thereof;

FIG. 3 is a right side elevational view thereof and the left side elevational view being a mirror image thereof;

FIG. 4 is a rear elevational view thereof;

FIG. 5 is a top plan view thereof; and,

FIG. 6 is a bottom plan view thereof.

The broken lines in the drawing depict portions of the beverage maker that form no part of the claimed design.
